Be it known that David Leneman, a subject of the King of Great Britain but having declared his intention of becoming a citizen of the United States, and resident of the Borough of Manhattan, county of New York, city and State of New York, has invented a new, original, and ornamental Design for a Necktie, of which the following is a specification, reference being had to the accompanying drawing, forming part there-

of, in which the figure is a perspective view of the necktie embodying my new design.

The stippling shown on the figure indicates various colors which distinguish different geographical divisions.

I claim:
